Co-pending U.S. Appl. No. 61/721,870, filed Nov. 2, 2012.

Primary Examiner — Derrick Holland

Assistant Examiner — Lauren Calve

(57) **CLAIM**

The ornamental design for a cable connector, as shown and described.

DESCRIPTION

FIG. 1 is a perspective view of a cable connector of my new design.

FIG. 2 is a second perspective view of the cable connector of FIG. 1.

FIG. 3 is a front view of the cable connector of FIG. 1.

FIG. 4 is a bottom view of the cable connector of FIG. 1.

FIG. 5 is a left side view of the cable connector of FIG. 1.

FIG. 6 is a top view of the cable connector of FIG. 1; and,

FIG. 7 is a right side view of the cable connector of FIG. 1.

The broken line showing of a cable connector represents unclaimed subject matter and forms no part of the claimed design.
